(57) **CLAIM**

We claim the ornamental design for a lock assembly, as shown and described.

DESCRIPTION

FIG. 1 is a perspective view of a lock assembly according to a first preferred embodiment of our new design;

FIG. 2 is a second perspective view of the lock assembly of FIG. 1;

FIG. 3 is a left side elevational view of the lock assembly of FIG. 1;

FIG. 4 is a right side elevational view of the lock assembly of FIG. 1;

FIG. 5 is a front elevational view of the lock assembly of FIG. 1;

FIG. 6 is a rear elevational view of the lock assembly of FIG. 1;

FIG. 7 is a top plan view of the lock assembly of FIG. 1; and,

FIG. 8 is a bottom plan view of the lock assembly of FIG. 1.

The dashed lines in FIGS. 1-8 represent environment and are for illustrative purposes only and do not constitute part of the claimed design. The phantom lines in FIGS. 1-8 define the border between claimed and unclaimed matter.
